United States Patent Office.

R. M. BROOKS, OF GRIFFIN, GEORGIA.

Letters Patent No. 79,309, dated June 30, 1868.

IMPROVED RAILROAD-RAIL.

The Schedule referred to in these Letters Patent and making part of the same.

TO ALL WHOM IT MAY CONCERN:

Be it known that I, R. M. BROOKS, of Griffin, in the county of Spaulding, and in the State of Georgia, have invented certain new and useful Improvements in Railroad-Rails; and do hereby declare that the following is a full, clear, and exact description thereof, reference being had to the accompanying drawings, and to the letters of reference marked thereon.

The nature of my invention consists in making a railroad-bar in two parts; one the bottom part, with a tongue in its centre to run into the groove on the hollow bar or cap, and in having the flanges on the sides of the hollow bar or cap notched or corrugated, so as to fit into similar notches or corrugations in the flanges of the sides of the bottom part. This is for the purpose of imparting additional strength to the rail.

To enable others skilled in the art to make and use my invention, I will proceed to describe its construction and operation.

In the annexed drawings, forming part of this specification, A represents the bottom rail, made with a tongue, C, in its centre, and its sides protected with flanges *a a*. The insides of these flanges have a series of notches or corrugations cut into them. B represents the top rail or cap, which is made hollow to allow the tongue C, on the bottom rail A, to enter, and the flanges *b b*, projecting from the sides of this hollow top rail or cap B, are also provided with notches or corrugations, which, when the cap is put on the bottom rail, fit into the notches already described as being on the bottom rail, which is shown in Figure 2.

By this arrangement the rails will be remarkably strong, so much so, that if the notched rails were laid down a quarter of a mile on each side of and on a bridge, they would be sufficiently strong to hold up and support a heavy train if the arches of the bridge should by any accident give way, thus preventing disaster and loss of life.

Having thus fully described my invention, what I claim as new, and desire to secure by Letters Patent, is—

The combination of the railroad-rails A and B, provided with corrugated flanges *a a* and *b b*, and fitting together, substantially as and for the purpose set forth.

In testimony that I claim the foregoing, I have hereunto set my hand, this 22d day of April, 1868.

R. M. BROOKS.
